UNITED STATES PATENT OFFICE

WILLIAM H. BOWDEN, OF NEWTON, IOWA, ASSIGNOR TO THE MAYTAG COMPANY, OF NEWTON, IOWA, A CORPORATION OF DELAWARE

WRINGER SAFETY FEEDER

Application filed October 31, 1927. Serial No. 229,979.

The object of my invention is to provide a wringer safety feeder of simple, durable and inexpensive construction.

More particularly, it is my purpose to provide a device for feeding clothes to a wringer of the type using rolls, which device is arranged to rock toward and from the wringer rolls, and is preferably actuated from the rotating roll.

10 Still another object of my invention is to provide a wringer equipped with a feed and having parts so constructed and arranged that the said device can be easily and readily adjusted from one side to the other of the wringer.

With these and other objects in view, my invention consists in the construction, arrangement and combination of the various parts of my wringer safety feeder, whereby 20 the objects contemplated are attained, as hereinafter more fully set forth, pointed out in my claims, and illustrated in the accompanying drawings, in which:

Figure 1 is a top or plan view of a wringer 25 equipped with a safety feeder embodying my invention, one end of the wringer being shown in horizontal cross section.

Figure 2 is a detail, sectional view taken on the line 2—2 of Figure 1.

30 Figure 3 is a detail, sectional view taken on the line 3—3 of Figure 1; and

Figure 4 is an enlarged, detail, sectional view illustrating the means for locking the spindles in their notches or slots.

35 In the accompanying drawings, I have shown a wringer which may be of the type now commonly used, having the lower longitudinal member indicated in the drawings by the reference numeral 10 and the spaced, opposite end members 12.

A lower wringer roll 14 has a shaft 15 journaled in the end members 12 and provided at one end with gearing mechanism 16, through which rotation may be imparted to 45 the roll 14.

Pivoted to the frame members 12 at the top thereof are the arms 18. The arms 18 are connected by a cover strap 20.

50 A release member in the form of a connecting cover 22 has at its ends the arms or

fingers 24 pivoted to the arms 18 near their free ends. The release 22 coacts with hook members 26 for locking the upper wringer roll 28 in position.

The wringer roll 28 has the shaft 30 journaled in the arms 18.

The structure above described is standard and forms no part of my present invention, except that the upper wringer roll 28 of the wringer used with my safety feeder, should 60 be capable of being moved upwardly and substantially away from the roll 14.

In Figure 3, I have shown in dotted lines the upper roll swing upwardly and out of the way.

The wringer is also provided at each end and near its opposite sides with lugs 32, having slots 34 in their upper ends. These lugs are for supporting the feeder.

My improved feeder comprises a channel-shaped member 36 having the inset end walls 38. The walls 38 have near their upper and lower parts projecting spindles 40.

The two lower spindles 40 are dropped into the slots 34 of the lugs 32 at one side of the wringer. Each end member 38 has midway between its spindles 40 a lug 42, extending longitudinally outwardly. (See Figures 1 and 3.)

80 In order to hold the spindles 40 in the slots 34, I have provided in the lugs 32, spring actuated pins 60 with rounded inner ends, past which the spindles 40 can be forced. The pins 60 serve to hold the spindles 40 in place, as illustrated for instance in Figure 4, against 85 accidental removal.

For connecting the feed with the lower wringer roll, and thus providing means for actuating the feeder, I provide the following 90 means:

On the shaft 15 of the lower wringer roll 14 at each end of the roll is fixed an eccentric disc 44. A band or ring 46 is received on the disc 44 and has a projecting arm 48 terminating in the reduced portion 50, which is slidably extended through the lug 42, as shown in Figure 1.

On the reduced portion 50 is a coil spring 52, which is held against the lug 42 by a cotter 100

pin or the like 54, extended through the outer end of the reduced portion 52.

Referring now to Figure 3, it will be seen that when the lower wringer roll is rotated, the eccentric disc 44 will give to the band 46 and the arm 48 a reciprocating motion. This will be transmitted to the lugs 42 and thus to the wringer feeder.

The wringer feeder will thus be rocked 10 upon its lower spindles 40 from its position shown in Figure 3 to the position shown in Figure 2 and back.

In feeding the garments to the wringer, the garments are laid over the upper part of 15 the member 36, when that member is at its outer position, as illustrated in Figure 3. Then as the roll 14 rotates, the feeder will be rocked to the position shown in Figure 2, where the upper part thereof will stand in 20 the position shown in Figure 2 for feeding the garments to the wringer rolls.

When the feeder is rocked back to the position shown in Figure 3, another garment can be laid on it to be fed to the wringer.

25 If it is desired to change the feeder from one side of the wringer to the other, the upper wringer roll is released and swung upwardly out of the way by the standard mechanism, and the feeder is swung upwardly across and 30 part way around the lower wringer roll, from its full line position shown in Figure 3 to its dotted line position shown in that figure.

The spindles 40, which were the upper spindles when the feeder was on the left side 35 of the wringer, as shown in Figure 3, will after the change be received in the slots 34 of the right-hand lugs 32, and when the upper roller is again replaced in position as shown in Figure 3, the feeder can be used on the 40 right-hand side of the wringer.

It will be seen that there is thus provided a feeder, the upper part of which rocks or reciprocates toward or from the line between the two wringer rolls.

45 The feeder is actuated by the operation of the wringer rolls themselves. It may be conveniently swung from one side of the wringer to the other.

The importance of a wringer safety feeder 50 will be readily seen. It frequently occurs that during the wringing operation, the hand of the operator is caught in the wringer roll and seriously crushed or mangled. This is a danger which becomes more important on 55 account of the fact that wringers are now operated by power.

With a device of the kind shown here, the danger of catching the operator's fingers or hand is very largely eliminated.

60 I have in the drawings herewith illustrated one form in which my wringer safety feeder may be embodied. It is not my purpose to limit myself to that particular form of feeder, nor to the particular mounting or 65 manner of operation herein set forth, but it

is my purpose to cover by my claims any modified forms of structure or use of mechanical equivalents, which may be reasonably included within their scope.

I claim as my invention:

1. In a device of the class described, the combination of a wringer having rolls with a feeder having an intermediate portion and having at its upper part a face at a substantial angle to the intermediate portion, means 70 for pivotally supporting the lower part of the feeder for rocking movement, and means for imparting rocking movement of the feeder face toward and from the lower part of the upper wringer roll.

2. In a device of the class described, the combination of a wringer having rolls with a feeder, means for pivotally supporting the feeder for rocking movement, and means for imparting rocking movement of the feeder to 75 ward and from the bite between the wringer rolls, said means including an operative yieldable connection between the feeder and one of the rolls.

3. In a device of the class described, the 80 combination of a wringer having rolls with a feeder, means for pivotally supporting the feeder for rocking movement, and means for imparting rocking movement of the feeder toward and from the bite between the wringer 85 rolls, said means including an eccentric fixed with relation to one of the wringer rolls, and an annular member on the eccentric having an arm connected with the feeder, slidably and yieldably for allowing automatic adjustment 90 of the feeder for articles of varying thickness and to permit the feeder to be pulled away from the rolls to avoid accidents.

4. In a device of the class described, a 95 wringer having rolls, and having journaling 100 means at its lower part on opposite sides of the rolls, a feeder for said wringer, comprising a member extending lengthwise of the wringer and provided near its lower and upper edges with pivots adapted respectively to 105 engage said journaling means on each side of the wringer, and means for rocking said feeder for alternately moving the upper part thereof toward the bite between the wringer 110 rolls and away from such bite.

115 5. In a structure of the class described, the combination of a wringer having a frame and having lower and upper rolls, the lower roll having a shaft journaled on the frame, the upper roll being supported for movement to 120 position for cooperating with the lower roll during the use of the wringer and for movement away from the lower roll, a feeder, means for operatively connecting said feeder with the shaft of the lower wringer roll for 125 imparting reciprocating movement to the feeder when the lower wringer roll is rotated, means on the frame on opposite sides of the rolls for pivotally supporting the feeder at points below its connection with the lower 130

wringer roll shaft, whereby when the feeder is being operated the upper part thereof rocks toward and from the wringer rolls for feeding garments to the rolls, and whereby when the upper roll is raised the feeder may be swung over the lower roll and pivotally supported on the opposite side thereof from its original position without disconnecting it from the lower roll shaft.

10 6. In a device of the class described, the combination of a pair of rolls, a pivoted feed member adapted to be rocked, said member comprising a sheet portion adapted to guard the operator from contact with one of said rolls, and a laterally extending part of said member having an edge adapted to approach and recede from the bite of said rolls and a part adapted to approach closely to the other roll at a substantial distance from said 15 bite during said rocking.

7. In a wringing machine, a pair of superimposed rolls and a feeder member pivotally supported below the bite of said rolls and adapted to be rocked, said feeder member comprising a sheet portion substantially guarding the lower roll on the feed side of the machine, an inwardly turned portion having an edge adapted to enter into close proximity to the bite of the rolls and having 20 a shoulder adapted to approach closely the upper roll at a substantial distance from said bite.

8. In a wringing machine, a pair of superimposed rolls and a feeder member pivotally supported below the bite of said rolls, means associated with said rolls for rocking said feeder member, said feeder member comprising a sheet portion substantially guarding the lower roll on the feed side of the 25 machine, an inwardly turned portion having an edge adapted to enter into close proximity to the bite of the rolls and having a shoulder adapted to approach closely the upper roll at a substantial distance from said bite.

40 9. In a wringing machine, a pair of superimposed rolls and a feeder member pivotally supported below the bite of said rolls, means associated with said rolls and yieldably connected to said feeder member for rocking said feeder member, said feeder member comprising a sheet portion substantially guarding the lower roll on the feed side of the machine, an inwardly turned portion having an edge adapted to enter into close proximity to the bite of the rolls and having a shoulder adapted to approach closely the upper roll at a substantial distance from said bite.

45 10. A wringer comprising a frame, an upper roll, a lower roll, a pivotal feeder member provided at its upper and lower ends with means for pivoting same on said frame below the bite of the rolls, means connecting a roll to an intermediate part of said feeder member and adapted to cause same to rock,

said upper roll being movable upwardly to permit the feeder member to be passed from one side of the wringer to the other.

11. A wringer comprising a frame, a pair of rolls, a pivoted feeder member on one side of the rolls, eccentrics mounted at the end of one roller and within said frame and connections between eccentrics and the feeder member for the purpose of rocking the same.

12. In a wringer having a frame and upper and lower rolls, drive means for the rolls, a feeder member pivoted in said frame, means driven by the drive means for rocking said feeder member, said driven means including a resilient means associated with said rocking means and feeder member for permitting movement between the same.

13. In a wringer having a frame and upper and lower rolls, drive means for the rolls, a feeder member pivoted in said frame, means driven by the drive means and slidably carried by said feeder member for rocking the same, said driven means including a means for resiliently connecting said slidable means and said feeder member.

Des Moines, Iowa, October 26, 1927.
